CLIP FOR AUTOMOTIVE SPARKPLUG, DISTRIBUTOR OR CAPACITOR

Albert Mazeika, Chicago, Ill., assignor to Milton Manufacturing Company, Inc., Chicago, Ill., a corporation of Illinois

Filed Nov. 6, 1967, Ser. No. 9,290

Term of patent 14 years

Int. Cl. D8—02

U.S. Cl. D54—1

Fig. 1.

Fig. 2.

Fig. 3.

Fig. 4.

FIG. 1 is a perspective view of a clip for automotive sparkplug, distributor or capacitor, showing my new design, the opposite side being substantially the same;

FIG. 2 is a side elevational view thereof, the opposite side being substantially the same;

FIG. 3 is a front elevational view thereof;

FIG. 4 is a rear elevational view thereof.

I claim:

The ornamental design for a clip for automotive sparkplug, distributor or capacitor, as shown and described.
